GRINDING MACHINE

William D. Schmidt and Harold L. Blood,
Worcester, Mass., assignors to The Heald
Machine Company, Worcester, Mass., a cor-
poration of Massachusetts

Application November 3, 1937, Serial No. 172,582
In Great Britain October 12, 1936

23 Claims. (Cl. 51—165)

The present invention relates to grinding machines and particularly to a machine in which the grinding wheel is a conductor of electricity and thus forms one contact in a circuit by which to control or procure changes in the machine operation. This application is a continuation-in-part of applicants' copending application, Serial No. 68,291, filed March 11, 1936.

In internal grinding machines the workpiece and grinding wheel at the start of each grinding operation, are usually offset from each other transversely of the machine so that, as the wheel or workpiece is moved longitudinally of the machine, the grinding wheel may enter the bore of the workpiece without engagement therewith. After the wheel is within the bore a relative crossfeed movement is imparted to bring the wheel and workpiece into grinding contact and thereafter to procure successively deeper and deeper cuts in the workpiece until the latter reaches the desired finished size.

Similarly, in external grinders, the wheel initially occupies a retracted position, in order to avoid any interference with the insertion of an unground workpiece in the machine. The crossfeed movement between the wheel and workpiece then brings the wheel against engagement with the workpiece surface and thereafter feeds the wheel into the workpiece for the cutting operation. In both internal and external grinders the time interval between the beginning of the crossfeed movement and the occurrence of actual contact between the wheel and work is unproductive machine time and accordingly the rate of this preliminary crossfeed should be as rapid as possible.

In prior machines the rate of this preliminary unproductive crossfeed movement before the grinding wheel engages the work has generally been the same as the rate of the initial rough grinding feed and consequently the unproductive part of each grinding operation is much longer than would be necessary if the grinding wheel could be given a very rapid relative crossfeed movement until the instant of contact between workpiece and grinding wheel. One of the principal objects of the present invention is accordingly to provide for a rapid transverse or crossfeed movement between the wheel and the workpiece until the wheel and workpiece are in engagement, at which time the rate of crossfeed movement is reduced to the desired roughing feed.

Grinding machines in which there are two or more different rates of crossfeed movement are

well known, as for example, in the Conradson Patent No. 1,534,302, dated April 21, 1925, the Taylor Patent No. 1,682,673, dated August 28, 1928, or the Blood and Burns Patent No. 2,027,627, dated January 14, 1936, but in the machines of each of these patents the rate of crossfeed movement initially established is not changed or reduced until the workpiece has been ground to a predetermined size slightly smaller than that of the desired finished size. None of these machines contemplates a reduction in the rate of crossfeed movement upon contact between the grinding wheel and workpiece. The present invention contemplates the reduction of the rate of crossfeed movement in each successive machine cycle immediately upon engagement between the grinding wheel and workpiece independently of variations in the diameter of the bores of the successive unground workpieces. It will be apparent that the machines of the aforesaid patents could not be adjusted to provide this reduction in the rate of crossfeed movement at the desired time since the successively ground workpieces invariably would vary in unfinished diameter.

In the machine of the Blood Patent No. 1,970,645, dated Aug. 31, 1934, the rate of crossfeed movement is diminished when the wheel engages the workpiece by the use of a light responsive element energized by the sparks resulting from contact between the grinding wheel and workpiece. Although this device is entirely satisfactory in operation, it necessitates the use of such elements as the light responsive element, a relay actuated thereby, and mechanism actuated by the relay for reducing the rate of crossfeed movement, thereby increasing the cost of construction of the machine. Moreover, a device of this character is not broadly applicable to the grinding of all types of workpieces since certain materials, when being ground, do not emit sparks with a sufficient light intensity to energize the light responsive element. If a liquid coolant is used, the latter may also prevent the formation of enough sparks to energize the light responsive element. A further object of the present invention is accordingly to provide for reducing the rate of crossfeed movement immediately upon contact between the grinding wheel and workpiece by a mechanism actuated directly by such contact rather than indirectly thereby.

One feature of the invention resides in the control of the workpiece size by means of an electrical circuit which includes the grinding

wheel. To this end a contact is positioned in predetermined spaced relation to the axis of rotation of the workpiece, and in a position to be engaged by the grinding wheel while the latter is in grinding engagement with the workpiece. This contact may be engaged by the wheel before the workpiece reaches finished size and thereby procure a runout of the wheel for dressing, or may be engaged by the wheel when the workpiece reaches finished size to terminate the grinding operation. In any event it is the engagement between the wheel and the contact, during the crossfeed movement between the wheel and workpiece which completes a circuit through the grinding wheel and thereby procures a change in the grinding operation.

According to the present invention the rate of feeding movement is reduced by using the grinding wheel as an electrical conductor and establishing a circuit through the grinding wheel and workpiece when these members come together with this circuit operating to procure the desired change in the grinding operation. Other and further objects and advantages of the invention will more fully appear from the following description taken in connection with the accompanying drawings in which—

Fig. 1 is a front elevation of a machine embodying the invention.

Fig. 2 is a plan view of the machine of Fig. 1. Fig. 3 is a large scale vertical section substantially along the line 3—3 of Fig. 2.

Fig. 4 is a vertical section substantially along the line 4—4 of Fig. 3, parts being broken away to show more clearly the crossfeed mechanism.

Fig. 5 is a plan view of a part of the crossfeed mechanism.

Fig. 6 is a fluid pressure diagram.

Fig. 7 is a wiring diagram.

Fig. 8 is a fragmentary front elevation showing a portion of the table controlling mechanism.

Fig. 9 is a side elevation of the chuck with certain parts broken away and shown sectionally.

Fig. 10 is an end elevation of the chuck of Fig. 9.

Like reference characters refer to like parts in the different figures.

Referring first to Fig. 1, the machine base supports a reciprocating table 1 as usually provided in an internal grinding machine; either the grinding wheel or the work to be ground is carried on said table, the reciprocations of the latter operating in either case to produce a relative axial movement between said grinding wheel and the workpiece. In the construction shown the table supports and carries a workhead 2 and the wheelhead 3 is mounted on a bridge 4 which spans the guideways 5, Fig. 3, provided by the machine base 6 for the movements of the table 1. The grinding wheel 7 is carried on a spindle 8 journaled in the wheelhead 3 and is suitably rotated at a high rate of speed by any well known mechanism, which in the present instance consists of a motor, not shown, in the base of the machine connected by a belt, also not shown, to a pulley 9, Fig. 7, on the grinding wheel spindle. The workpiece a is mounted in a suitable work-supporting structure which may be in the form of a chuck 10 carried on a spindle 11 journaled in the workhead. The chuck 10 is preferably driven at a relatively slow rate of speed from a motor 12 connected to the spindle 11 by a belt 13. A clutch mechanism 14 of any desired or well-known structure provides for stopping the rotation of the chuck

without interfering with the rotation of the motor 12. Said clutch is under the control of a handle 15 easily accessible to the operator of the machine.

The reciprocation of the table 1 to cause the desired relative axial traverse between the rotating grinding wheel and the work-supporting structure is imparted in any well known manner, as by the use of fluid pressure controlling and reversing mechanism, one type of which is described in the Head and Guild Patent No. 1,582,468, dated April 27, 1926. A similar type of mechanism is disclosed in the Blood and Burns Patent No. 2,011,705, dated Aug. 20, 1935. It is sufficient to note for the purpose of the present application that reversal of the table is procured at each end of the normal working stroke by spaced reversing dogs 16 and 17 which are carried by blocks 18 and 19 adjustably mounted on the front of the table 1 and adapted alternately to engage and move a reversing lever 20. The reversing lever is connected by suitable mechanism to a reversing valve 21, (see Fig. 6). The reverse lever 20 as shown in Fig. 8 is provided with two spaced upstanding arms, the right hand arm adapted to be struck by the reversing dog 16 and the left hand arm adapted to be struck by the reversing dog 17, to obtain the desired movements of valve 21 during the time that the grinding wheel is within the bore of the workpiece.

Referring now to Fig. 6, a pump 22 driven by a motor 23 directs fluid under pressure from the sump 24 through a pipe 25 to a casing 26 for the reversing valve 21. The casing 26 has an inlet port 27 to which the pipe 25 is connected and also has spaced outlet ports 28 and 29 connected by pipes 30 and 31 respectively to the left and right hand ends of a cylinder 32 mounted in the base of the machine. A piston 33 slidable in the cylinder has a piston rod 34, the end of which is connected to a depending lug 35 on the table 1. The reversing valve 21 serves in the well known manner to direct the fluid under-pressure supply alternately through ports 28 and 29 to opposite ends of the cylinder 32, for the reciprocation of table 1 and to connect each of said ports alternately to an exhaust port 36 which returns the fluid to the sump 24.

The crossfeed movement between the workpiece and the grinding wheel is obtained by transverse movement of the wheelhead 3 on the bridge 4. Movement of a cross slide 37, Fig. 3; on which the wheelhead is mounted, is effected by rotation of the crossfeed screw 38 suitably journaled in said bridge and held against endwise movement by the anti-friction bearings 39 applied to a reduced portion of said screw. The thread of the crossfeed screw engages an internally threaded portion 40 of the cross slide for effecting the transverse movement thereof. On the outer end of the crossfeed screw 38 is mounted a gear 41 which meshes with a gear 42 secured to a shaft 43 journaled in a housing 44 for the crossfeed mechanism. Also secured to the shaft 43 in spaced relation to the gear 42 is a ratchet wheel 45 engageable by the spaced and oppositely directed pawls 46 and 47, Fig. 4, carried by an annular member 48 secured to a sleeve 49 journaled on the shaft 43. The sleeve 49 has an integral pinion 50 engageable by a rack 51 horizontally slidable on a suitable support 52 in the casing 44. The rack 51 is shiftable back and forth by a fluid pressure mechanism, hereinafter described in detail, to procure, through 75

the pawl and ratchet arrangement, the rotative movements of the shaft 43, and accordingly slight angular movements of the crossfeed screw for the advance and retraction of the cross slide 37. Manual rotation of the crossfeed screw is by a hand wheel 43' on the end of the shaft 43.

The pawl and ratchet arrangement is fully described in the Guild Patent No. 1,971,138, dated Aug. 21, 1934, or in the Blood and Burns Patent No. 2,011,705, above referred to. It is sufficient to note for the purpose of the present application that this double pawl arrangement permits, during the return of the cross slide to original position in readiness for a subsequent grinding operation, a compensation for the reduction in size of the grinding wheel as a result of wear and the dressing operation performed thereon during the preceding grinding operation. With reference to Figs. 3 and 4, it will be noted that both of the pawls are normally held in operative engagement with the ratchet by a spring 53, so that a rotation of the annular member 48 provides a corresponding rotation of the ratchet 45. The pawl 47 is operative for the feeding movement or advance of the cross slide, and the pawl 46 is operative for the retraction of the cross slide. The pawl 46 is rendered inoperative during a part of the movement of the annular member 48 in the counterclockwise direction so that the cross slide is retracted a slightly shorter distance than it is moved forward during the crossfeed movement.

To obtain this compensatory action, the shaft 43 has journalled thereon an arm 54 having a gear segment 55 on the outer end thereof. The gear segment engages with a pinion 56 carried on a shaft 57 journalled in the front wall of the housing 44. The outer end of the shaft 57 has a knurled knob 58 by which said shaft is turned to adjust the position of the arm 54. Integral with the arm 54 is a cam 59 in a position for engagement with a pin 60 on the pawl 46. The cam 59 is adjusted to be engaged by the pin 60 just before the termination of the crossfeed movement and accordingly, during the first part of the retraction of the cross slide, the pawl 46 is permitted to engage with the ratchet wheel 45; in other words, despite the reverse rotation of the annular member 48, there is no corresponding movement of the ratchet wheel until the pawl has moved far enough counterclockwise to clear the cam 59.

Referring now to Figs. 4 and 6, the rack 51 is carried on the end of a piston rod 61 extending from a piston 62 slidable in a horizontally positioned cylinder 63 mounted on the front of the bridge 4. Fluid under pressure is directed alternately to opposite ends of the cylinder 63 for procuring first the crossfeed movement of the slide 37 and subsequently the retraction thereof. As shown in Fig. 6, fluid under pressure from the pipe 25 passes through a pipe 64 to the inlet port 65 of a reversing valve casing 66 for a reversing valve 67 associated with the crossfeed mechanism. An outlet port 68 in the casing is connected by a pipe 69 to the left hand end of the cylinder 63, and another outlet port 70 is connected by a pipe 71 and through suitable valve mechanisms, hereinafter described, to the right hand end of said cylinder. An exhaust port 72 for the reversing valve casing provides for exhaust of fluid from the left hand end of the cylinder when fluid under pressure is directed to the right hand end.

The admission of fluid to the right hand end

of the cylinder 63 from the valve 67 is controlled by a horizontally slideable valve 73 positioned in a casing 74 mounted above the cylinder 63. The pipe 71, in which is disposed a main throttle valve 75, of any suitable construction, connects with a channel 76 in the block 77 in which the valve casing 74 is positioned. A channel 78 intersects the channel 76 and provides a direct connection to the port 79 in the casing 74. A transverse channel 80, also intersecting the channel 76, provides a connection from said channel to spaced vertical bores 81 and 82 in the block 77 in which are positioned respectively, the valves 83 and 84. The valve 83 controls the rate of crossfeed movement for rough grinding, which is established by initial engagement between the grinding wheel and workpiece and the valve 84 controls the rate of crossfeed movement for fine grinding during the latter part of the grinding operation. These valves 83 and 84 are substantially of the same construction employed for the rough grinding feed valve and fine grinding feed valve disclosed by the aforesaid Blood and Burns Patent No. 2,027,627, and are manually adjustable by their exterior knurled knobs to vary the flow of pressure fluid therethrough.

A channel 85 in the casing 74 and the block 77, and an intersecting channel 86 in the cylinder 63, provide a fluid connection from the valve 73 to the right hand end of the cylinder. With the valve 73 in the position shown, fluid under pressure from the pump under the control of the throttle valve 75, passes around the reduced portion 87 of the valve 73 to enter the right hand end of the cylinder, thereby procuring a rapid preliminary crossfeed movement of the grinding wheel to bring the grinding wheel and workpiece into engagement. As soon as the grinding wheel and workpiece engage each other the valve 73 in the manner hereinafter described is shifted to the right to close the substantially unthrottled fluid connection around the reduced portion 87 of the valve and provide fluid connection around a reduced portion 88 from a channel 89 connecting with the bore 81. In this position of the valve 73 the rate of crossfeed movement is appreciably throttled down, being under the control of the coarse feed valve 83 for the rough grinding operation.

The valve 73 is normally held in the position of Figs. 4 and 6 by mechanism best shown in Figs. 4 and 5. Referring to Fig. 4, the block 77 has a plunger 90 slidable therein in line with the valve 73 and at the left hand end thereof. The plunger 90 carries on its left hand end a roller 91 engageable successively, during the crossfeed movement, with cams 92 and 93 carried by the annular member 48 which also carries the pawls 46 and 47. Movement of the plunger 90 to the left beyond the position of Fig. 4, is limited by a cap 94 positioned in the end of the bore in which the plunger is slidable. A coil spring 95, which is positioned in a recess 96 in the block 77, engages with the right hand end of the valve 73 and normally holds said valve in engagement with the plunger 90.

For movement of the valve to the right, when the grinding wheel engages the workpiece, a coil spring 97 is positioned between the right hand end of the casing 74 and a ring 98 surrounding a reduced portion 99 of the valve 73. The ring 98 is normally held in the inoperative position shown, but is released when the grinding wheel engages the workpiece to engage the flange 100 on the end of the valve 73, thereby urging said valve to the right. The movement of the ring 98 is lim-

ited by engagement with a shoulder 101 in the block 77.

With reference now to Fig. 5, the structure by which the ring 98 is held inoperative involves spaced parallel pins 102 slidably in the block 77 and engaging with the ring 98. The outer ends of these pins are engaged by one end of a lever 103 pivoted on a pin 104 carried by projecting flanges 105 on the block 77. The other end of the lever 103 has an adjustable screw 106 engageable with the lower end of a lever 107 pivoted on a pin 108 also carried by the parallel flanges 105. The opposite end of the lever 107 is secured by a pin 109 to the armature 110 of a solenoid 111, which, at the beginning of the grinding operation, is energized, to draw the armature to the left, and thereby urge the ring 98 to the position of Fig. 4.

With reference to Fig. 7, one terminal of the solenoid 111 is connected by a lead 112 to one side of a source of electrical power 113 and the other terminal of the solenoid is connected by a lead 114 to a contact 115. A connector 116 normally establishes a circuit between the contact 115 and a contact 117 which is connected by a lead 118 to the other side of the power supply 113. The connector 116 is carried by the armature 119 of a solenoid 120, one terminal of which is connected by a lead 121 to a second source of electrical power 122, which in the diagrammatic showing of Fig. 7, is the secondary coil of a transformer. The other terminal of the solenoid 120 is connected by a lead 123 to a ground 124, and the same terminal is also connected by a lead 125 to the contact 126 of a switch 127 which is normally closed. The opposite contact 128 of the switch 127 is connected by a lead 129 to a contact 130, the latter being in a position to be engaged by the connector 116 when the solenoid 120 is energized. Another contact 131, also engageable with the connector 116, is connected by a lead 132 to that side of the source of power 122 which is opposite to the one that is connected to the lead 121. The lead 132 is connected by a lead 133 to the wheelhead 3, which, as best shown in Fig. 3, is insulated from the cross slide 37 by suitable strips of insulating material 134.

The grinding wheel 7 is treated to be a conductor of electricity, as by any desired or well known means, which may be, for example, by impregnating the wheel with an electrolyte, and accordingly the wheel can form a part of a circuit. The workpiece or the workholding structure carrying the workpiece is connected to a ground 135, and accordingly, when the workpiece and grinding wheel move into engagement as a result of the crossfeed movement, a circuit is established through the grinding wheel to energize the solenoid 120, the latter moving the connector 116 into engagement with contacts 120 and 131 to establish a holding circuit through the solenoid 120 for the remainder of the grinding operation. The movement of the connector 116 by the solenoid 120 breaks the circuit through the solenoid 111, allowing the armature thereof to move to the right to release the ring 98 for movement of the valve 73 to the right under the action of the spring 87.

The valve 73 having been shifted to the right by the ring 98, this movement occurring upon engagement between the grinding wheel and workpiece, as will be apparent, the grinding operation continues with the grinding wheel still given a relatively rapid crossfeed movement for the coarse or rough grinding operation. This

rate of crossfeed movement, which is under the control of the valve 83, continues until the cam 92 engages the roller 91, Fig. 4, thereby shifting the valve 73 even further to the right to cut off the flow of fluid through the channel 89 and to direct fluid around the reduced portion 136 of the valve 73 to a channel 137 which intersects the channel 86. Fluid passing around the reduced portion 136 must also pass through the fine feed valve 84, so that the crossfeed movement is materially reduced and is very slow for the purpose of producing a fine finish on the workpiece.

The grinding operation continues with a relatively slow crossfeed movement until the roller 91 is engaged by the cam 93, thereby moving the valve 73 still more to the right to cut off the fluid connection from the fine feed valve 84 to the channel 137. The full-size portion 138 of the valve 73 which cuts off the flow of fluid to the channel 137 has a plurality of very small axial grooves 139 which permit a very small amount of fluid to enter the cylinder 63, so that during this last part of the grinding operation the crossfeed movement is throttled down to such a slow rate as to be almost negligible, for a sparking-out operation.

The grinding operation may, for example, be under the control of any suitable gage mechanism or under the control of the crossfeed movement such as the Blood and Burns Patent No. 2,011,705, dated Aug. 20, 1935. Regardless of the type of size-control mechanism used, the grinding wheel and workpiece are adapted to be axially separated at the completion of each grinding operation by rendering the reversing dog 17 inoperative. Simultaneously, the valve 67 is shifted to the position shown in Fig. 6 by suitable mechanism not shown, in order to obtain the usual retraction of the cross slide 37. This shifting of the valve 67 allows fluid under pressure to enter the left hand end of the cylinder 63 for movement of the piston 62 to the right. At the same time fluid under pressure from the left hand end of the cylinder 63 passes through a channel 140 which connects said cylinder to the valve 73 at the left hand end of said valve and between said valve and the plug 90. As fluid under pressure enters between the valve and plug the valve is shifted to the right to uncover a port 141 to allow fluid to exhaust through the channels 86, 137, and the channel 142 connected to the port 141. This channel directs the exhaust fluid back to the sump, the fluid to the channel passing around a reduced portion 142' of the valve 73.

As the table moves to the left to rest or loading position, a cam 143 carried by the table, engages with the actuator 144, Fig. 7, of the switch 127, thereby opening the circuit through the solenoid 120 to allow the connector 116 to return to the position of Fig. 7 in readiness for a subsequent grinding operation.

The operation of the machine, which will no doubt be clear from the foregoing description, will be briefly summarized. With the machine in the position of Fig. 1, and with a workpiece *a* located in the workholding structure 10, the latter is set in rotation by movement of the handle 15. The table is then moved to the right to bring the workpiece and grinding wheel into operative position by movement of the lever 145 which is connected to the reversing valve 21 and which moves the latter from the position shown into a position to direct fluid under pressure to the left hand end of the table cylinder. As the table

reaches operative grinding position the valve 67 is shifted by any suitable mechanism, but preferably in response to the table movement, to direct fluid under pressure from the pipe 64 to the pipe 71 for procuring the crossfeed movement between the grinding wheel and the workpiece.

At the beginning of the crossfeed movement the valve 73 is in the position of Figs. 4 and 6 and the rate of the crossfeed movement is accordingly 10 under the control of the throttle valve 75 which provides for a crossfeed movement at a rapid rate to quickly bring the grinding wheel and workpiece into engagement. Thus the time involved in the inoperative part of the grinding 15 operation is substantially reduced by this rapid crossfeed movement. As soon as the grinding wheel engages the workpiece a circuit is established through the grinding wheel and workpiece to energize the solenoid 120, thereby deenergizing 20 the solenoid 111 to cause the valve 73 to move to the right. The coarse feed valve 83 is thus rendered operative for a crossfeed movement of the grinding wheel relative to the workpiece at a rate suitable for rough grinding. This rate is materially slower than the preliminary crossfeed 25 movement prevailing before the grinding wheel becomes operative.

After this reduction in the rate of the crossfeed movement, the grinding operation continues until 30 the valve 73 is shifted to the right by engagement between the cam 92 and roller 91, for reducing the crossfeed movement to a fine feed rate. A still further reduction occurs when the cam 93 engages the roller 91. After the grinding 35 wheel has reduced the workpiece to the desired size, as determined by any suitable size-controlling device, the table is withdrawn to the left for an axial separation of the grinding wheel from the workpiece and the cross slide 37 is retracted by shifting the valve 67 to the position of Fig. 6, this shifting movement being preferably under the control of the same mechanism which procures the axial separation of the wheel and workpiece.

As the table reaches the rest position shown, the solenoid 120 is deenergized by actuation of the switch 127 to again energize the solenoid 111 in readiness for the subsequent grinding operation. It may be noted that the reduction in size of the grinding wheel is compensated for during the retraction of the cross slide by a delay in operation of the pawl 46 due to the cam 59 above described. It may be further noted that during any axial separation of the workpiece and grinding wheel either at the completion of the grinding operation, or before completion of the grinding operation, as for a dressing operation on the wheel or for any other purpose, the cross slide may be temporarily shifted transversely of the machine to avoid the objectionable bell-mouthing which occurs when the grinding wheel is maintained in engagement with the workpiece instead of being retracted during the axial separation. This structure is best shown in Fig. 2 and involves a lever 146 actuated by a cam 147 carried by the table. Rocking of the lever 146 by the cam 147 temporarily shifts the crossfeed screw axially to back the wheel away from the work. This structure is not a part of the present invention and need not be described.

70 The impregnated grinding wheel may also be utilized for controlling the machine operation still further and may operate in connection with the structure above described, or separately therefrom, as will hereinafter appear. One change in the grinding operation which may be under the

control of the impregnated grinding wheel is a termination of the grinding operation when the workpiece is ground to a predetermined diameter. To this end the wheel is engageable with a contact positioned in predetermined relation to the axis 5 of the workpiece and the engagement between the wheel and the contact closes a circuit by means of which the grinding operation is terminated, or such other change in the grinding operation is procured as may be desired.

With reference to Fig. 8, the grinding operation may be under the control of a mechanism similar to that of Patent No. 2,011,705, above referred to. The table movements are under the control of the reversing dogs 16 and 17, which, as above described, are pivotally mounted on blocks 18 and 19 respectively, and alternately engage and rock the reversing lever 20, the latter being suitably connected to the reversing valve 21. When the grinding operation is completed, or when a run-out of the table is desired, the dog 17 is raised into an inoperative position (to pass the lever 20) by means of a lever 148 pivoted at 149 on the front of the machine. The lever 148 has an integral arm 150, the end of which engages a pin 151 on a depending arm 152 pivotally mounted on the pin 149. A latch 153 holds the arm 152 in the position shown and a spring 154 is arranged to cause counterclockwise movement of the arm 152 when the latch 153 is released. This counterclockwise movement of the arm 152 causes a corresponding upward movement of the lever 148, placing the upper end thereof in a position to engage and elevate the dog 17, thereby preventing the dog from engaging with the reversing lever so that the normal reversal of the table does not take place and the latter continues its movement to the left until the grinding wheel and workpiece have been axially spaced from each other.

For actuating the latch 153, the latter has an integral depending arm 155 engageable with the end of the armature 156 of a solenoid 157 mounted on a bracket 158 on the front of the machine. Energization of the solenoid causes movement of the armature 156 to the left and corresponding disengagement of the latch 153.

Referring now to Fig. 7, the solenoid 157 is positioned in a circuit which includes the grinding wheel. One terminal of the solenoid is connected by a lead 159 to the lead 121 from one side of a secondary coil of the transformer 122. The other terminal of the solenoid 157 is connected by a lead 160 through a collector ring, hereinafter described, to a contact 161 positioned in the work-head. When the grinding wheel 7, which as above stated, is a conductor of electricity, touches the end of the contact 161, a circuit through the solenoid 157 is completed, thereby terminating the grinding operation by causing elevation of the dog 17 through lever 148, thus to produce the axial separation of the grinding wheel and workpiece.

The contact 161, as best shown in Figs. 9 and 10, is positioned radially within the chuck 10 and is insulated therefrom. To this end a ring of insulation 162 is positioned in a groove 163 in the outer surface of the chuck and a collector ring 164 is positioned in a groove in the periphery of the insulating ring 162. The contact 161 is in the form of a threaded rod which extends radially inward of the chuck from the collector ring and the inner end of the contact is in a position for engagement by the grinding wheel when the workpiece is ground to a predetermined finished diameter. The contact is obviously spaced from the axis of 75

the workpiece a distance exactly equal to the radius of the finished workpiece surface, as will be apparent. A brush 165 is mounted on the table 1 and is suitably insulated therefrom, being carried on a spring finger 166 so that the brush is held resiliently against the collector ring 164.

As the grinding operation continues after the grinding wheel and workpiece are brought into engagement, the grinding action progresses in the usual manner until the grinding wheel, during its usual axial reciprocation over the surface of the workpiece, engages the contact 161. When this occurs a circuit through the solenoid 157 is completed, thereby disabling the dog 17, thus to obtain a run-out of the table.

It will be apparent that in certain instances, where the contact 161 is not positioned within the chuck, the contact may be located outside of the chuck in a position for engagement by the grinding wheel, the contact in this case being mounted on a suitable bracket, not shown, insulated from the remainder of the machine. Where the contact is fixed in this manner it is preferably in the same horizontal plane as the axis of the grinding wheel. It will be understood that the particular advantage of positioning the contact 161 within the chuck in the position shown is to facilitate the removal and insertion of workpieces in the chuck. In certain instances the inner end of the contact 161 may be in the form of a ring whose inner diameter corresponds exactly to the finished diameter of the workpiece and with the ring concentric to the axis of the workpiece.

From the foregoing it will be apparent that the invention provides for a change in the machine operation by engagement between the grinding wheel, which is a conductor of electricity, and the workpiece itself, or a contact positioned in predetermined relation to the axis of the workpiece. This change in the machine operation may be a reduction in the rate of crossfeed movement when the grinding wheel engages the workpiece, and, following this change, the grinding wheel, by engaging a contact member, procures a second change by withdrawing the wheel and work from engagement with each other. Either of the changes above noted may be procured separately and independently of the other change, as will be apparent. The changes in the grinding operation are under the control of electrical circuits, each of which includes the grinding wheel, and it will be understood that the circuit established by engagement between the grinding wheel and a contact in a position for engagement with the wheel may procure any other changes in the machine operation instead of, or in addition to the changes above outlined.

We claim:

1. In a grinding machine, a grinding wheel, a work-supporting member adapted to support a workpiece, fluid pressure actuated means for procuring a crossfeed movement between the wheel and the workpiece in the work-supporting member, valve means controlling the admission of fluid pressure to said means, and means responsive to engagement between the wheel and workpiece for shifting said valve.
2. In a grinding machine, a grinding wheel, a work-supporting member adapted to support a workpiece, fluid pressure actuated means for procuring a crossfeed movement between the wheel and the workpiece in the work-supporting member, and means responsive to engagement between the wheel and workpiece for throttling

flow of fluid to said fluid pressure actuated means, to reduce the rate of crossfeed movement.

3. In a grinding machine, a grinding wheel, a work-supporting member adapted to support and rotate a workpiece, fluid pressure actuated means for procuring a feeding movement between the wheel and a workpiece in the work-supporting member, and means operative in response to initial engagement between the wheel and the workpiece for changing the rate of flow of fluid to said fluid pressure means.

4. In a grinding machine, a grinding wheel, a work-supporting member, fluid pressure means for procuring a feeding movement of the wheel relative to a workpiece in the work-supporting member, a valve for said fluid pressure means, and means responsive to engagement between said wheel and work for shifting said valve, said last means including a solenoid.

5. In a grinding machine, a grinding wheel, a work-supporting member, fluid pressure means for procuring a feeding movement of the wheel relative to a workpiece in the work-supporting member, a valve for said fluid pressure means, and means responsive to engagement between said wheel and work for shifting said valve, said last means including a solenoid for shifting said valve, and a circuit through said solenoid, said circuit having spaced contacts, one of which is the grinding wheel, and the other of which is a workpiece in the work-supporting member, whereby the circuit is closed by contact between the wheel and workpiece.

6. In a grinding machine, a work-supporting member adapted to support a workpiece, a grinding wheel and a circuit including said wheel and workpiece and closed by engagement therebetween, said circuit also including means for procuring a change in the machine operation.

7. In a grinding machine, a work-supporting member adapted to support a workpiece, a grinding wheel and a circuit in which the grinding wheel forms one contact and the workpiece forms another, said circuit being closed by engagement between the wheel and workpiece.

8. In a grinding machine, a grinding wheel, a work-supporting member adapted to support a workpiece, means for procuring a crossfeed movement between the grinding wheel and a workpiece in the work-supporting member, a circuit including means for procuring a change in the rate of crossfeed movement, and means directly responsive to positive engagement of the grinding wheel and workpiece for changing the normal state of the circuit.

9. In a grinding machine, a grinding wheel, a work-supporting member having a workpiece therein, means for procuring a crossfeed movement between the wheel and the workpiece in the work-supporting member, means responsive to initial engagement between the wheel and a workpiece in the work-supporting member for procuring a change in the machine operation, means subsequently operative during the crossfeed movement for reducing the rate thereof, and additional means operative prior to completion of the grinding operation for further reducing the rate of crossfeed movement.

10. In a grinding machine, a grinding wheel, a work-supporting member adapted to support a workpiece, fluid pressure actuated means for procuring a feeding movement between the wheel and a workpiece in the work-supporting member, a valve for controlling the admission of fluid to said fluid pressure actuated means, means opera-

5 tive in response to initial engagement between the wheel and workpiece for reducing the rate of feeding movement by shifting of said valve, and means subsequently operative during the 10 grinding operation for a further shifting movement of said valve for further reducing the rate of crossfeed movement.

11. In a grinding machine, a work-supporting member adapted to support a workpiece, a grinding wheel, an electrical circuit, means responsive to engagement between the wheel and work for breaking said circuit, and means included in the circuit and operative on breaking of said circuit for procuring a change in the machine operation.

15 12. In a grinding machine, a work-supporting member adapted to support a workpiece, a grinding wheel, an electrical circuit, said circuit including a workpiece in the work-supporting member and the grinding wheel, the latter being a conductor of electricity, said circuit being closed directly by engagement between the grinding wheel and the workpiece, and means included in said circuit and operative upon closing of said circuit for procuring a change in the machine 20 operation.

13. In a grinding machine, a grinding wheel, a work-supporting member adapted to support a workpiece, fluid pressure means for procuring a feeding movement between the wheel and a workpiece in the work-supporting member, a valve for controlling the admission of fluid to said means, a circuit including a solenoid for holding said valve in a predetermined position, a second circuit, including the grinding wheel and workpiece, the latter being a conductor of electricity, for opening the first circuit upon engagement between the grinding wheel and workpiece.

14. In a grinding machine in combination, a grinding wheel which is a conductor of electricity, 40 electrically actuated means for procuring a change in the machine operation, a circuit including said electrically actuated means and the grinding wheel, and a contact in said circuit and engageable by the grinding wheel for completing the circuit by which the electrically actuated means are 45 rendered operative.

15. In a grinding machine in combination, a work-support, a grinding wheel which is a conductor of electricity, an electrical circuit, including the grinding wheel, a contact in said circuit, associated with the work-support and engageable with the wheel during the operation of the machine for completing the circuit, and electrically actuated means operated by the closing of said circuit for procuring a change in the 55 machine operation.

16. In a grinding machine, a workholder, a grinding wheel, an integral portion of which is a conductor of electricity, means for procuring a grinding operation on a workpiece in the workholder, a contact positioned in predetermined relation to the axis of the workpiece and in a position for engagement with the grinding wheel during the grinding operation, a circuit including 60 said contact and said wheel and closed by engagement between the wheel and contact, and means controlled by said circuit for procuring a change in the grinding operation.

17. In a grinding machine, a workholder, a 70 grinding wheel, an integral portion of which is a conductor of electricity, means for procuring a grinding operation on a workpiece in the workholder, a contact positioned in predetermined relation to the axis of the workpiece and in a position for engagement with the grinding wheel dur-

ing the grinding operation, a circuit including said contact and said wheel and closed by engagement between the wheel and contact, and means controlled by said circuit for terminating the grinding operation.

18. In a grinding machine, a workholder, a grinding wheel, an integral portion of which is a conductor of electricity, a contact located in predetermined relation to the axis of the workholder and in a position for engagement by the grinding wheel, a circuit including said wheel and contact, and means under the control of said circuit for separating the wheel from a workpiece in the workholder.

19. In a grinding machine, a workholder, a grinding wheel, an integral portion of which is a conductor of electricity, a contact located in predetermined relation to the axis of the workholder and in a position for engagement by the grinding wheel, a circuit including said wheel and contact, and means under the control of said circuit for terminating the grinding operation.

20. In a grinding machine, a workholder, a grinding wheel, an integral portion of which is a conductor of electricity, means for procuring a grinding operation on a workpiece in the workholder, a contact positioned in the workholder in predetermined relation to the axis thereof and in a position for engagement with the grinding wheel during the grinding operation, a circuit including said contact and said wheel and closed by engagement between the wheel and contact, and means controlled by said circuit for procuring a change in the grinding operation.

21. In a grinding machine, a workholder, a grinding wheel, an integral portion of which is a conductor of electricity, means for procuring a grinding operation on a workpiece in the workholder, a contact within the workholder in predetermined relation to the axis of the workpiece and adjacent to the inner end of the workpiece for engagement with the grinding wheel during the grinding operation, a circuit including said contact and said wheel and closed by engagement between the wheel and contact, and means controlled by said circuit for procuring a change in the 35 grinding operation.

22. In a grinding machine, a workholder, a grinding wheel, an integral portion of which is a conductor of electricity, means for procuring a crossfeed movement between the grinding wheel and the workholder for a grinding operation on a workpiece in the workholder, a circuit including the grinding wheel and workpiece and closed by engagement between the wheel and workpiece, 50 means under the control of said circuit for procuring a change in the machine operation, a contact positioned in predetermined relation to the axis of the workpiece in a position for engagement with the grinding wheel during the grinding operation, a circuit including said contact and said wheel, and closed by engagement between the contact and wheel, and means controlled by said 55 last circuit for procuring another change in the grinding operation.

23. In a grinding machine, a workholder, a grinding wheel, an integral portion of which is a conductor of electricity, means for procuring a crossfeed movement between the grinding wheel and the workholder for a grinding operation on a 70 workpiece in the workholder, a circuit including the grinding wheel and workpiece and closed by engagement between the wheel and workpiece, means under the control of said circuit for procuring a change in the machine operation, a con-

tact positioned in predetermined relation to the axis of the workpiece in a position for engagement with the grinding wheel during the grinding operation, a circuit including said contact and said wheel, and closed by engagement between the contact and wheel, and means controlled by

said last circuit for procuring another change in the grinding operation, said circuits being successively closed for controlling each of said change procuring means independently.

WILLIAM D. SCHMIDT. 5
HAROLD L. BLOOD.

CERTIFICATE OF CORRECTION.

Patent No. 2,206,732.

July 2, 1940.

WILLIAM D. SCHMIDT, ET AL.

It is hereby certified that error appears in the printed specification of the above numbered patent requiring correction as follows: Page 1, first column, line 27, for the word "against" read --into--; line 29, for "into" read --against--; and that the said Letters Patent should be read with this correction therein that the same may conform to the record of the case in the Patent Office.

Signed and sealed this 10th day of September, A. D. 1940.

Leslie Frazer,

(Seal)

Acting Commissioner of Patents.
